U.S. Appl. No. 12/421,753, filed Apr. 10, 2009, entitled "Cleaning Sponge,".

(Continued)

Primary Examiner — Cynthia E Ramirez

CLAIM

(57) The ornamental design for a cleaning material on a cleaning tool, as shown and described.

DESCRIPTION

FIG. 1 is a perspective view showing the new design for cleaning material on a cleaning tool.

FIG. 2 is a left-side view thereof;

FIG. 3 is a right-side view thereof;

FIG. 4 is a back view thereof;

FIG. 5 is a front view thereof;

FIG. 6 is a top view thereof; and,

FIG. 7 is a bottom view thereof.

The broken lines showing form no part of the claimed design.
